(57) **CLAIM**

The ornamental design for an applicator as shown and
described.

DESCRIPTION

FIG. 1 is a top perspective view a first embodiment of an
applicator in accordance with our new design;

FIG. 2 is a front view thereof;

FIG. 3 is a rear view thereof;

FIG. 4 is a right side view thereof;

FIG. 5 is a left side view thereof;

FIG. 6 is a bottom view thereof;

FIG. 7 is a top view thereof;

FIG. 8 is a top perspective view of a second embodiment of
an applicator in accordance with our new design;

FIG. 9 is a front view thereof;

FIG. 10 is a rear view thereof;

FIG. 11 is a right side view thereof;

FIG. 12 is a left side view thereof;

FIG. 13 is a bottom view thereof; and,

FIG. 14 is a top side view thereof.

The broken lines in the drawings illustrate portions of the
applicator that form no part of the claimed design.

1 Claim, 6 Drawing Sheets
